SHOE MACHINE

Francis L. Brandt, Marblehead, Mass., assignor
to United Shoe Machinery Corporation, Ber-
ough of Flemington, N. J., a corporation of
New Jersey

Application June 27, 1940, Serial No. 342,677

36 Claims. (Cl. 12—7)

This invention relates to shoe machines and is herein illustrated in its application to machines for use in the manufacture of prewelt shoes. Machines of the type herein illustrated operate to force the forepart of a last into the forepart of a prewelt upper, then to last the upper by means of wiper plates constructed and arranged to operate within the welt crease, and finally, to hold the upper in lasted position by means of the wiper plates while a sole is attached to the welt. A machine of this type is illustrated in United States Letters Patent No. 2,042,518, granted June 2, 1936, on an application of Karl Engel.

It is an object of the present invention to provide a machine of this type which is inexpensive to manufacture and which permits a high rate of production while affording greater accuracy and uniformity of lasting than heretofore obtained in machines of this type.

With a view to affording a high degree of accuracy and uniformity in the lasting of uppers by machine, this invention provides lasting wipers arranged for bodily rectilinear closing movements having predetermined components lengthwise and widthwise of a shoe in the machine, the directions of closing movements of said wipers changing at a predetermined point in their operation in order to provide two stages of wiper movement for a purpose now to be explained. During the first stage of their closing movement, the wipers are advanced in paths so arranged as to afford a short, direct initial movement into a position in which their wiping edges define an outline having the same configuration as the periphery of the sole portion of a shoe on which the wipers are intended to operate; and during the second stage of the closing of the wipers this configuration is maintained in order that the wipers may operate accurately and uniformly on a run of sizes of shoes. This construction permits the use of a minimum number of wipers. For example, only four sets of wipers are required for lasting shoes from infants' size 1 to 10½, each set of wipers operating on two and one-half sizes. In order to maintain a predetermined orientation of the wipers relatively to each other during their operation, the wipers are interconnected by means herein illustrated as dowels which slide in suitable bores in the wiper carriers. In accordance with a further feature of the invention, the wipers are held on their carriers by means permitting convenient and rapid interchange of wipers, said means including a hold-down mem-

ber which is out of registration with the wipers when the wipers are retracted and therefore need not be moved to permit removal of the wipers. The wipers are located on the carriers, without securing them to the carriers, by means herein illustrated as pins which enter suitable holes provided in the wipers.

For supporting the toe portion of a prewelt upper, a work support is arranged to engage the upper in the welt crease and hold the welted margin slightly above position to receive the lasting wipers in order to facilitate movement of the wipers into a position beneath the welt, and the machine, in accordance with a further feature of the invention, is provided with means operable at the will of the operator to move the work support downwardly to bring the upper into position to receive the wipers. For forcing the forepart of a last into the forepart of an upper supported by its welted margin, the illustrated machine is provided with means herein illustrated as a last depressor which operates automatically during the downward movement of the work support to move the last downwardly with the upper, thus preventing movement of the last out of the upper. As herein illustrated, the depressor comprises a last-engaging member movably mounted in a carrier in which is also mounted means for yieldingly pressing said member against the last.

For pressing the rear part of the last upwardly against the overlasted margin of the upper and supporting it during the sole-attaching operation, the illustrated machine is provided with a last support, a wedge for applying upward pressure to said support, and a toggle which may alternatively be advanced bodily with the wedge or actuated to apply heavy pressure to the wedge. In the operation of the machine, the wedge and toggle are advanced as a unit to lift the work support until it meets resistance, whereupon the toggle is straightened to advance the wedge forcibly and thus to cause the work support to press the last upwardly against the overlasted margin of the upper. In order to permit adjustment of the last support lengthwise and widthwise of the shoe, the last support and the pressure-applying assembly are mounted in a carriage arranged for adjustive movement lengthwise and widthwise of the shoe. It will be understood that the last-depressing means and the means for applying upward pressure to the last are not limited in their utility to their illustrated embodiment in a prewelt shoe machine, but are applicable to machines for oper-

ating on other types of shoes and to machines which perform operations other than lasting operations.

These and other features of the invention will now be described with reference to the accompanying drawings and pointed out in the appended claims.

In the drawings,

Fig. 1 is a perspective view of a machine embodying the features of the present invention, certain parts being broken away to show operating mechanisms; 10

Fig. 2 is a plan view, partly broken away, the wipers and wiper carriers at one side of the machine being removed to show the mechanism for guiding and directing the movements of the wipers; 15

Fig. 3 is a sectional elevation on the plane of the longitudinal median line of a shoe in the machine showing a shoe on the work support ready to be lasted; 20

Fig. 4 is an elevation on the same plane as Fig. 3 showing the operating mechanisms as they appear after the lasting operation has been completed, certain parts being broken away and other parts shown in section; 25

Fig. 5 is a perspective view of a lasting wiper and its carrier and the wiper hold-down mechanism;

Fig. 6 is a sectional view taken on the line VI—VI of Fig. 4; and 30

Fig. 7 is a perspective view of the toe supporting means.

Referring to Fig. 1, the illustrated machine comprises a frame 10 adapted to rest on a bench or other suitable support, the top of said frame being provided with a suitable shoe-receiving opening. Mounted for rotary movement on a top plate 12 (Figs. 2 and 3) and guided by the arcuate edge faces of guide plates 13 is a flat ring which in the illustrated machine comprises a metal top plate 14 and a wooden base plate 15 within the central openings of which the shoe to be operated upon is positioned. The illustrated machine is adapted to operate only on infants' shoes and children's shoes of the smaller sizes. In order to provide sufficient room within the ring for the largest size shoe on which the machine is intended to operate, the inner margin of the ring is cut away at 16 to provide clearance for the rear part of the shoe. Mounted on the upper surfaces of the plates 13 and the ring 14, which surfaces, as shown in Fig. 3, lie in a common plane, are four wiper carriers 18 (Figs. 2 and 3) the inner edge faces of which provide a generally rectangular shoe-receiving opening. The wiper carriers in their movements relatively to each other are guided in rectilinear paths by dowels 20 (Fig. 2) mounted in horizontal bores extending into the carriers at right angles to their edge faces. These dowels cause the wipers to close in unison and at a common rate of speed, and they also serve to maintain a suitable arrangement of the carriers relatively to each other such that the wiping edges of the wipers will be in alignment during the lasting operation. Two forepart-lasting wipers 22 and two rear-part-lasting wipers 24 rest on the upper surfaces of the wiper carriers and are located relatively to the carriers by pins 26 (Figs. 1 and 5) projecting upwardly from the carriers through suitable holes in the wipers. For holding the wipers against upward movement away from their carriers during the lasting operation, hold-down plates 28 are secured to the end walls of the 75

frame 10 by clamping screws 30 which extend through transverse slots 32 in the hold-down plates. To assist in holding the wiper plates against upward movement away from the carriers, two hold-down plates 34, only one of which is shown in the drawings, are secured to the bottom of the horizontal portions of brackets 36 secured to the frame and extending inwardly over the adjacent margins of the wipers at opposite sides of the shoe-receiving opening, each hold-down plate being adjustable vertically by means of a screw 38 mounted in the end of the bracket 36. Referring to Fig. 2, it will be seen that the illustrated hold-down plate 34 is out of registration with the wipers when the wipers are fully retracted and when it is desired to remove the wipers from the machine, all that is required is to turn the screws 30 sufficiently to permit the hold-down plates 28 to slide outwardly away from the wiper plates so that the wiper plates may be lifted off their carriers. For guiding and directing the movements of the wipers relatively to a shoe in the machine, each wiper carrier is provided with two pins 40 (Fig. 2) which extend downwardly from the wiper carrier into angular cam slots 42 in diagonal plates 44 mounted in grooves in the top of the frame. These cam slots are identical in construction and arrangement and extend from their outer extremities in paths radial to the path of movement of the ring 14 and are arranged at angles of 45 degrees to the longitudinal median line of a shoe in the machine. The inner portions of the slots 42 are arranged at an obtuse angle to their outer portions and extend toward the center of the machine in parallel paths which converge toward the longitudinal median line of a shoe in the machine at angles of approximately 13 degrees. Thus, it will be seen that the wipers in the course of their inward movements travel in rectilinear paths the directions of which change at predetermined points thus providing two stages of movement of the wipers in the first of which their movement has equal components lengthwise and widthwise of a shoe in the machine and in the second of which their components of movement lengthwise of the shoe are much greater than their components of movement widthwise of the shoe. When the wipers have advanced to the point where their paths of movement change, their wiping edges define an outline having the same configuration as the contour of the sole portion of a shoe on which the wipers are intended to operate. In operating upon the largest size in the run of sizes for which the wipers are provided, the wiping operation is completed when the wipers come to the limit of their 45-degree motion. It will be understood that in operating upon the largest size in the run, the wipers in their closed position will be separated from each other at opposite sides of the shank portion of the shoe approximately three-quarters of an inch. If desired, these portions, which the wipers do not reach, may be lasted by hand, for example, by means of a boning tool; but ordinarily, it will not be found necessary to do any hand lasting since the comparative rigidity of the welt will usually insure a proper lasting of these portions of the upper. In operating on the smaller sizes in the run, the wipers enter the second stage of their movement, the extent of which varies in accordance with the size of the shoe being operated upon. In operating on the smallest size in the run the wipers come into abutting relation to

each other both at the ends of the shoe and at the sides of the shoe upon completion of their closing movement and provide a continuous support for the outwardly extending margin of the welt. During the second stage of their movement the configuration defined by the wiping edges of the wipers at the end of their 45-degree movement is maintained in order that the wipers may operate accurately and uniformly on all sizes of shoes within the run. This result is accomplished by arranging the inner portions of the slots 42 at an angle of 13 degrees to a line parallel to the longitudinal median line of the shoe. It has been found that this arrangement of the slots 42 produces a wiper motion in which the ratio of movement lengthwise of the shoe to movement widthwise of the shoe corresponds to the ratio of the difference in length to the difference in width from one size shoe to another. The difference in length from size to size is one-third of an inch and the difference in width from size to size is one-twelfth of an inch, and, accordingly, the wipers during the second stage of their movement move lengthwise and widthwise of the shoe at a ratio of four to one. It will be understood that the 45-degree wiper motion enables the wipers to be retracted to a position permitting convenient removal of the shoe from the machine by the shortest possible wiper motion.

For simultaneously operating the wipers, the ring 14 is provided with four slots 46 (Fig. 2) uniformly spaced from each other and arranged to receive pins 48 extending downwardly from the wiper carriers 18. These slots are so constructed and arranged relatively to the wiper carriers that the wipers advance rapidly during the first stage of their movement when the shoe offers no resistance to their movement and advance slowly after the wipers have entered the welt crease of the upper in order that the lasting operation may be effected with a minimum of exertion on the part of the operator by reason of the ratio of the movement of the actuating means to the movement of the wipers. For actuating the ring 14, a cam plate 50 (Fig. 1) is secured to a rock shaft 52 provided with a hand lever 54, said cam plate having a groove 56 in which travels a cam roll at one end of a bell crank lever 58 freely mounted on a shaft 60 and connected by a link 62 to a slide 64 which carries in a transverse groove 66 a block 68 swiveled on a pin 70 extending downwardly from the ring 14.

For supporting the toe portion of a prewelt upper, for example, the upper 12, illustrated in Fig. 3, the machine is provided with a work-supporting plate 74 (Figs. 3 and 7) having upwardly extending fingers 75 the ends of which enter the welt crease of the upper and support the upper by engagement with the seam securing the welt to the upper. The plate 74 is bent around a block 76, the peripheral contour of which corresponds generally to the outline of the toe portion of a shoe, said plate being secured to the curved edge face of the block 76 by a screw 78, and to the opposite sides of the block by two screws 80 extending through horizontal slots at opposite end portions of the plate. The side portions of the plate 74 spring outwardly against the heads of the screws 80 and by turning said screws, the plate may be adjusted to arrange the upper supporting fingers to support different sizes of uppers. The block 76 is supported on a vertically sliding shaft 82 which has secured to its upper end a plate 84 which is T-shaped in cross section widthwise of the shoe and fits into a T-groove

86 in the bottom of the block 76, said T-groove having an open end at the curved end of the block 76 and terminating in an end wall 88 which engages the end of the plate 84 to locate the toe-supporting assembly lengthwise of a shoe in the machine. The shaft 82 is slidably mounted in a hollow post 90 fixed to the base of the machine. When the machine is at rest, the toe-supporting assembly is at the limit of its upward movement as seen in Fig. 3 in which position the fingers 75 hold the welted margin of the upper at its toe end above the plane of the forepart wipers 22. In this position the toe-supporting assembly is supported by a toggle which operates in a recess in the post 90, said toggle comprising an upper link 92 pivotally mounted in the lower end portion of the shaft 82 and a lower link 94 which is secured to the rock shaft 60 by a pin 98 which is extended to provide an anchorage for a spring 100 which holds the toggle in straightened position. For breaking the toggle to move the toe-supporting assembly downwardly thereby to bring the toe portion of the shoe into position to be operated upon by the forepart wipers, the rock shaft 60 is provided with a hand lever 102 (Fig. 1). As the forepart of the upper moves downwardly with the toe-supporting assembly, the welt 104 engages the margin of the forepart wipers and its downward movement is arrested by the wipers while the downward movement of the work-supporting assembly continues to carry the fingers 75 out of alignment with the forepart wipers to provide clearance for their operation. The block 76 together with the plate 74 is readily removable from the plate 84 by moving the block to the left, as seen in Fig. 3, when there is no shoe in the machine, the plate 74 being held against misplacement by the shoe itself during the operation of the machine. The machine is provided with two such removable toe-supporting units, one for right and the other for left shoes. It is not necessary to provide a plurality of toe-supporting units for different sizes of shoes since the toe-supporting plate 74 is adjustable widthwise by turning the screws 80.

The prewelt upper, when it is presented to the illustrated machine, is assembled on the rear part of a last and preferably secured in assembled position by a tack 106 driven through the rear part of the upper and into the last, but the forepart of the last projects outwardly through the bottom opening of the upper and must be forced into the upper preliminary to the lasting operation. For forcing the forepart of the last into the upper while the toe portion of the upper is supported by fingers 75, the illustrated machine is provided with a last depressor, illustrated in Fig. 1, comprising a slide 108 mounted in a vertical opening in an arm 110 mounted to swing on a vertical axis to carry the depressor assembly to and from operating position. The slide 108 has a longitudinal bore extending upwardly from its lower end in which is mounted a plunger 112 the lower end of which has a flat head 114 which engages the toe portion of a last, for example, the last 116 illustrated in Figs. 3 and 4. The plunger 112 is backed up by a spring 118 mounted in the socket in the slide 108, the plunger being retained within the socket by a pin 120 extending outwardly from the plunger through a longitudinal slot 122 provided in the slide 108. For operating the depressor, there is provided a toggle mechanism comprising a link 124 pivoted in an upward extension 126 of the arm 110, said link having a handle 128 for operating the tog-

gle, and lower toggle links 130 connecting the upper link to the upper portion of the slide 108. A pin 132 in the upward extension 126 of the arm determines the straightened position of the toggle. In the operation of the last depressing assembly, the slide 108 moves downwardly with the plunger 112 forcing the forepart of the last into the supported upper and after the last has come to the limit of its downward movement, the slide 108 continues its downward movement until the toggle has come into its straightened position, illustrated in Fig. 1, compressing the spring 118, as shown in Fig. 3. During the subsequent downward movement of the toe-supporting assembly from its position in Fig. 3 to its position in Fig. 4, the spring 118 expands to maintain a sufficient pressure against the plunger 112 to hold the last in a proper position within the toe portion of the upper for the subsequent lasting operation. The depressor assembly remains in operative position until the completion of the lasting operation whereupon the handle 128 is moved upwardly to break the toggle and lift the depressor from the last bottom, whereupon the arm 110 is swung into a remote position by a torsion spring 134 (Fig. 1).

After the upper has been lasted, the wipers 22 and 24 remain in their advanced positions to support the outward extension of the welt 104 while a sole is cement attached to the welt. It is important that the last be held firmly against the overlasted margins of the welt and upper during the cement attachment of the sole to the welt. At the toe end of the shoe, the tension of the upper itself is sufficient to hold the last firmly against the overlasted margins. In order to apply upward pressure to the rear part of the last to bring it forcibly against the overlasted margin of the upper and hold it rigidly in position while a sole is attached, the illustrated machine is provided with a work-support herein illustrated as a square post 136 slidably mounted in a square hole in a carriage 138 and having at its upper end a last pin 140 which is received within the last pin hole in the rear part of the last. The carriage 138 is mounted for longitudinal sliding movement in a groove 142 in a carriage support herein illustrated as a flat plate 144 which rests on the base of the frame and is fulcrumed thereto at 146 to permit swinging movement of the carriage for adjustment of the post 136 widthwise of the shoe. For moving the carriage 138 longitudinally in the support 144, a short arm 166 is secured to a shaft 168 and bifurcated at its lower end for engagement with a ball headed stud 170 extending upwardly from the carriage. The arm 166 is operated by a hand lever 172 formed by bending the outer end portion of the shaft 168 into the position illustrated in Fig. 1. For applying upward pressure to the post 136, a wedge 148 mounted for sliding movement between the walls 150 (Fig. 6) of the carriage acts against the inclined bottom face of the post 136 as the wedge is moved to the right as seen in Fig. 4. For operating the wedge, the illustrated machine is provided with a toggle mechanism comprising a pair of links 152 (Figs. 4 and 6) pivoted to a reduced extension 154 of the wedge and pivoted at their opposite ends to a toggle link 156 having a handle 158. Swiveled at opposite sides of the toggle link 156 are pawls 160 which are confined between the toggle link and the walls 162 (Fig. 6) of the carriage 138 and are provided with teeth which engage ratchet plates 164 secured to the walls 162 of the carriage, one

of said ratchet plates being illustrated in Fig. 4. When the toggle link 156 is resting against the bottom of the carriage 138, the teeth of the pawls 160 are out of engagement with the ratchet plates 164 and the toggle and the wedge may be slidably advanced as a unit with the toggle in its broken position, as illustrated in Fig. 3, to lift the post 136 until it meets resistance, whereupon the handle 158 is lifted, bringing the pawls 160 into engagement with the ratchet plates and straightening the toggle to advance the wedge forcibly against the end face of the post and move the post upwardly with sufficient force to press the bottom of the last hard against the overlasted margin of the upper. If desired, the operation of the toggle may be repeated to increase the pressure of the last against the upper, the frictional engagement of the wedge with the end face of the post 136 being sufficient to hold the wedge in position while the pawls are being advanced into a new position on the ratchet plates. It will be seen that the broken position of the toggle, as shown in Fig. 3, is determined by the engagement of the diagonal surface at the right end of the toggle link 156 with the top of the toggle-receiving chamber in the carriage 138.

In the operation of the illustrated machine, a prewelt upper, the rear part of which has been mounted on a last and attached thereto by the back-seam tack 106 (Fig. 3) is positioned in the machine, the last being mounted on the last pin 140 while the upper is positioned on the toe-supporting fingers 75. At this time the forepart of the last projects upwardly somewhat through the bottom opening of the upper. To bring the forepart of the last down into position for the lasting operation, the last-depressing assembly is operated by swinging the handle 128 (Fig. 1) downwardly into its position in Fig. 1, straightening the toggle 124, 130 and forcing the plunger 112 downwardly against the last. The wipers are then advanced until they are arrested by the engagement of the forepart wipers 22 with the toe-supporting fingers 75 (Fig. 3) whereupon the toe-supporting assembly is moved downwardly bringing the welt at the forepart of the upper into engagement with the wipers 22. During the downward movement of the toe-supporting assembly, the spring 118 in the depressor assembly maintains sufficient pressure of the plunger 112 against the last to hold the last in position on the upper. By supporting the forepart of the upper above the plane of the forepart lasting wipers 42, the initial advancement of said wipers into a position beneath the welt 104 is facilitated and accidental engagement of the wipers with the sole-attaching face of the welt is obviated. After the toe-supporting assembly has been moved downwardly into its position illustrated in Fig. 4, the wipers 22 and 24 are further advanced into their positions illustrated in Fig. 4 to complete the lasting operation. After the lasting has been completed, the wedge 148 is moved to the right, as seen in Fig. 4, to force the post 136 upwardly in order to press the overlasted margin of the upper firmly against the wipers, and while the last is supported by said post and the outward extension of the welt 104 is supported by the wipers, a filler (not shown) is positioned on the last bottom in the space enclosed by the adjacent edge faces of the welt and upper and a sole, previously treated with cement, is applied to the filler and the welt which have likewise been treated with cement. The sole

may be bonded to the welt and the filler in any suitable manner, for example, by pounding it with a hammer which is faced with rubber or other suitable material to prevent objectionably marking the sole. After the sole has been attached, the wipers are fully retracted, leaving the shoe free to be removed from the machine.

Having thus described my invention what I claim as new and desire to secure by Letters Patent of the United States is:

1. In a lasting machine, lasting wipers constructed and arranged for bodily rectilinear closing movements having predetermined components lengthwise and widthwise of a shoe in the machine, the directions of closing movements of said wipers changing at a predetermined stage in their operation.

2. In a lasting machine, lasting wipers, and wiper guiding means so constructed and arranged that the wipers have bodily rectilinear closing movements having predetermined components lengthwise and widthwise of a shoe in the machine, the directions of closing movements of said wipers changing at a predetermined stage in their operation so that thereafter the lengthwise component is greater than the widthwise component.

3. In a lasting machine, lasting wipers, and means having angular wiper guideways so constructed and arranged that the wipers have bodily rectilinear closing movements in two directions the first of which has substantially equal components lengthwise and widthwise of a shoe in the machine and brings the wipers into a position in which their wiping edges define an outline having the same configuration as the periphery of the sole portion of a shoe on which the wipers are intended to operate, the second direction of closing movement being such that the component of movement lengthwise of the shoe is greater than the widthwise component.

4. In a lasting machine, lasting wipers, wiper carriers, and supports on which the carriers are mounted and to which the carriers have roll and slot connections which guide the carriers and the wipers in bodily rectilinear closing movements in two directions the first of which has predetermined components lengthwise and widthwise of a shoe in the machine and brings the wipers into a position in which their wiping edges define an outline having the same configuration as the periphery of the sole portion of a shoe on which the wipers are intended to operate, the second direction of closing movement being such that the configuration defined by the wiping edges of the wipers is maintained while the opening enclosed by the wipers is reduced.

5. In a lasting machine, end lasting wipers constructed and arranged for bodily closing movements having predetermined components lengthwise and widthwise of a shoe in the machine, the directions of closing movements of said wipers changing at a predetermined stage in their operation so that thereafter the lengthwise component is greater than the widthwise component, and means interconnecting said wipers and maintaining a predetermined orientation of the wipers relatively to each other during their closing movements.

6. In a lasting machine, and lasting wipers constructed and arranged for bodily closing movements having predetermined components lengthwise and widthwise of a shoe in the machine, the directions of closing movements of said wipers changing at a predetermined stage in their oper-

ation so that thereafter the lengthwise component is greater than the widthwise component, the adjacent ends of said wipers coming into abutting relation to each other upon completion of their closing movements.

7. In a lasting machine, toe lasting wipers constructed and arranged for bodily closing movements having predetermined components lengthwise and widthwise of a shoe in the machine, the directions of closing movements of said wipers changing at a predetermined stage in their operation so that thereafter the lengthwise component is greater than the widthwise component, and heel lasting wipers having closing movements corresponding to the closing movements of the toe wipers.

8. In a prewelt lasting machine, a pair of toe lasting wipers, a pair of heel lasting wipers, means for operating said wipers, and means interconnecting the toe wipers and the heel wipers at opposite sides of the shoe and causing them to close in unison and at a common rate of speed, said interconnections maintaining a predetermined alignment and orientation of the wipers relatively to each other during their operation, said wipers upon the completion of their closing movements providing a substantially continuous support for the outwardly extending margin of the welt.

9. In a lasting machine, lasting wipers, means for imparting operative movements to the wipers, and means for guiding the wipers in two-directional bodily rectilinear closing movements.

10. In a lasting machine, the lasting wipers, wiper carriers, supports on which the carriers are mounted, and means connecting the carriers to the supports and guiding the carriers in two-directional bodily rectilinear closing movements.

11. In a lasting machine, lasting wipers, wiper carriers, a supporting frame on which the carriers are mounted, roll and slot connections from the carriers to the frame which guide the carriers and the wipers in two-directional bodily rectilinear closing movements, and means interconnecting said carriers and maintaining a predetermined orientation of the wipers relatively to each other during their closing movements.

12. In a lasting machine, the combination with lasting wipers, of a wiper hold-down member which is out of registration with a wiper on which it operates when said wiper is retracted.

13. In a lasting machine, the combination with lasting wipers and wiper carriers, of means for locating the wipers relatively to the carriers without securing the wipers to the carriers, and a hold-down means for preventing disengagement of the wipers from their carriers, including a wiper hold-down member which is out of registration with the wipers on which it operates when said wipers are retracted.

14. In a lasting machine, the combination with lasting wipers, of a wiper hold-down member which is out of registration with a wiper on which it operates when said wiper is retracted and another hold-down member which is readily movable from hold-down position.

15. In a lasting machine, the combination with lasting wipers and wiper carriers, of means for locating the wipers relatively to the carriers without securing said parts together, and means for preventing disengagement of a wiper from its carrier comprising a hold-down member which is out of hold-down position when the wipers are retracted, and another hold-down

member readily slidable to and from hold-down position.

16. In a lasting machine, the combination with fore-part lasting wipers and rear part lasting wipers constructed and arranged to wipe the entire margin of a shoe upper in the machine into lasted position, of two wiper hold-down members one at each side of the shoe constructed and arranged to engage the adjacent margins of the forepart and rear part wipers, said hold-down members being out of registration with the wipers when the wipers are fully retracted.

17. In a shoe machine, the combination with means for operating on a shoe in the machine, of a support constructed and arranged to engage a last in a shoe upper, means for applying pressure to said support, means for actuating said pressure-applying means, and means operable alternatively to advance said pressure-applying means and its actuating means as a unit or to operate said actuating means.

18. In a shoe machine, the combination with means for operating on a shoe in the machine, of a support constructed and arranged to engage a last in a shoe upper, means for applying pressure to said support, means for actuating said pressure-applying means, means operable alternatively to advance said pressure-applying means and its actuating means as a unit or to operate said actuating means, and a carriage for the last support, the pressure-applying means and its actuating means, said carriage being movable to adjust the last support lengthwise of a shoe in the machine.

19. In a shoe machine, the combination with means for operating on a shoe in the machine, of a support constructed and arranged to engage a last in the shoe, said support being adjustable both lengthwise and widthwise of the shoe, means for applying pressure to said support, means for actuating said pressure-applying means, and means operable alternatively to advance said pressure-applying means and its actuating means as a unit or to operate said actuating means.

20. In a shoe machine, the combination with means for operating on a shoe in the machine, of a last support, a wedge for applying pressure to said last support, actuating means for said wedge, and means operable alternatively to advance the wedge and its actuating means as a unit or to operate said actuating means to cause the wedge to apply pressure to the last support.

21. In a shoe machine, the combination with means for operating on a shoe in the machine, of a last support, a wedge for applying pressure to said support, a toggle for operating said wedge, and a member operable alternatively to advance the wedge and the toggle as a unit or to straighten the toggle to operate the wedge.

22. In a shoe machine, the combination with means for operating on a shoe in the machine, of a last support, a wedge for applying pressure to said support, and a toggle for operating said wedge, one element of said toggle being extended to provide a handle operable alternatively to advance the toggle and the wedge as a unit or to straighten the toggle to operate the wedge.

23. In a shoe machine, the combination with means for operating on a shoe in the machine, of a last support, a wedge for applying pressure to said support, a toggle for actuating said wedge, said wedge and toggle being movable as a unit, and means affording an abutment against which the toggle operates to actuate the wedge, said 70

abutment means being rendered operative by movement of one of the toggle elements.

24. In a shoe machine, the combination with means for operating on a shoe in the machine, of a last support, a wedge for applying pressure to said support, a toggle for actuating said wedge, said wedge and toggle being movable as a unit, and pawl and ratchet means affording an abutment against which the toggle operates to actuate the wedge.

10 25. In a shoe machine, the combination with means for operating on a shoe in the machine, of a last support, a wedge for applying pressure to said last support, a toggle for actuating said wedge, and a carriage for said last support, said wedge, and wedge actuating toggle, said carriage having a way in which the wedge and the toggle are mounted, the walls of parts of said way serving to determine the bent position of the toggle.

20 26. In a shoe machine, the combination with means for operating on a shoe in the machine, of a last support, a wedge for applying pressure to said last support, a toggle for actuating said wedge, a carriage for said last support, said wedge, and wedge actuating toggle, said carriage having a way in which the wedge and the toggle are mounted, the walls of parts of said way serving to determine the bent position of the toggle, means providing an abutment against which the toggle operates, and means carried by one of the toggle elements for engaging said abutment means.

27. In a shoe machine, the combination with means for operating on a shoe in the machine, of a last support, a wedge for applying pressure to said last support, a toggle for actuating said wedge, and a carriage for said last support, said wedge, and wedge actuating toggle, said carriage having a way in which the wedge and the toggle are mounted, the walls of parts of said way serving to determine the bent position of the toggle, said wedge and its actuating toggle being freely mounted in said carriage for sliding movement in the way provided therein.

35 28. In a shoe machine, the combination with means for operating on a shoe in the machine, of a last support, a wedge for applying pressure to said last support, a toggle for actuating said wedge, a carriage for said last support, said wedge, and wedge actuating toggle, said carriage having a way in which the wedge and the toggle are mounted, the walls of parts of said way serving to determine the bent position of the toggle, said wedge and its actuating toggle being freely mounted in said carriage for sliding movement in the way provided therein, and a support in which the carriage is slidably mounted for movement to adjust the last support lengthwise of the shoe, said carriage support being movable to adjust the last support widthwise of the shoe.

40 29. In a shoe machine, the combination with means for operating on a shoe in the machine, of a support constructed and arranged to engage a last in a shoe upper, means for applying pressure to said support, means for actuating said pressure-applying means, means operable alternatively to advance said pressure-applying means and its actuating means as a unit or to operate said actuating means, a carriage for said last support, said pressure-applying means and its actuating means, a support for the carriage on which the carriage is movable to adjust the last support lengthwise of a shoe in the machine, said carriage support being movable to adjust the last

support widthwise of the shoe, and means for moving the carriage on its support.

30. In a shoe machine, the combination with means for operating on a shoe in the machine, of a support constructed and arranged to engage a last in a shoe upper, means for applying pressure to said support, means for actuating said pressure-applying means, means operable alternatively to advance said pressure-applying means and its actuating means as a unit or to operate said actuating means, and a carriage for the last support, the pressure-applying means and its actuating means, said carriage being movable to adjust the last support lengthwise of and widthwise of a shoe in the machine.

31. In a prewelt shoe machine, a depressor for pressing a last into the forepart of an upper supported by its welted margin, said depressor operating automatically to move the last downwardly during a downward movement of the upper.

32. In a prewelt shoe machine, a depressor for forcing the forepart of a last into the forepart of an upper supported by its welted margin, said depressor comprising a last engaging member, a carrier for said member, and means in the carrier for yieldingly pressing said member against the last.

33. In a prewelt shoe machine, the combination with means constructed and arranged to operate within the welt crease of a shoe in the machine, of a work support constructed and arranged to act against the welt and to hold the welt above the path of movement of said operating means, means operable at the will of the operator to move the work support downwardly, and means operating automatically to move the shoe downwardly with the work support.

34. In a prewelt shoe machine, the combina-

tion with means for operating in the welt crease of a shoe in the machine, of a work support, a toggle which in its straightened condition holds a shoe on the support in a position such that its 5 welted margin is located above the path of movement of said operating means, means operable at the will of the operator for breaking the toggle, thereby to move the work support downwardly, and a depressor operating automatically 10 to move the shoe downwardly with the work support.

35. In a prewelt shoe machine, a combination with means for operating in the welt crease of a shoe in the machine, of a work support, a 15 toggle which in its straightened condition holds a shoe on the support in a position such that its welted margin is located above the path of movement of said operating means, means operable at the will of the operator for breaking the toggle thereby to move the work support downwardly, a depressor operating automatically to move the shoe downwardly with the work support, and means for yieldingly maintaining the straightened condition of the toggle.

36. In a prewelt shoe machine, the combination with means constructed and arranged to operate within the welt crease of a shoe in the machine, of a work support constructed and arranged to act against the welt and to hold the 25 welt slightly above the path of movement of said operating means, means operable at the will of the operator to move the work support downwardly, and means for moving the shoe downwardly with the work support, said means comprising a slide, a spring-pressed work-engaging element carried by said slide, and a manually 30 operated toggle for advancing the slide and holding it against return movement.

FRANCIS L. BRANDT.

CERTIFICATE OF CORRECTION.

Patent No. 2,261,219.

November 4, 1941.

FRANCIS L. BRANDT.

It is hereby certified that error appears in the printed specification of the above numbered patent requiring correction as follows: Page 5, first column, line 70, claim 6, for "and" read --end--; and second column, line 34, claim 10, strike out "the"; and that the said Letters Patent should be read with this correction therein that the same may conform to the record of the case in the Patent Office.

Signed and sealed this 13th day of January, A. D. 1942.

(Seal)

Henry Van Arsdale,
Acting Commissioner of Patents.
